UNITED STATES PATENT OFFICE.

ELMER R. CLEMENTS, OF RIVERTON, NEBRASKA.

HOG OILER.

Application filed June 22, 1926. Serial No. 117,816.

This invention relates to hog oilers and particularly to certain improvements on the hog oiler disclosed in my Patent No. 1,528,402, granted March 3, 1925. This 5 patent shows an oiler having a body supported at its lower end for oscillatory movement in all directions, the upper end of the body being hollow and being preferably of sheet metal having perforations adjacent its 10 upper extremity and also shows an oil container disposed within this hollow upper portion of the body and there being a wick or other absorbent material disposed between this container, which container is 15 fixed, and the wall of the oscillatory body so that as the hog presses against the body, the wick would be compressed and causes oil to be forced out upon the exterior surface of the body.

20 The general object of the present invention is to provide a structure generally that previously disclosed but in which provision is made for allowing oil to flow down onto the supporting base of the oiler so that 25 small pigs can also become oiled.

A further object is to provide improved means for supporting the oiling device proper and the reservoir and still another object is to provide means permitting this 30 reservoir to be easily filled without any loss of oil and without flooding the oiler.

My invention is illustrated in the accompanying drawings wherein:

Figure 1 is a vertical sectional view 35 through a hog oiler constructed in accordance with my invention;

Fig. 2 is a section on the line 2—2 of Figure 1;

Fig. 3 is a fragmentary elevation of the 40 casing.

Referring to these drawings 10 designates a base which may be of any suitable material and of any desired form but which is 45 illustrated as having a central socket 11 and a set screw 12. This base is mounted upon a supporting platform 13.

Disposed within the socket 11 in the base and held in place by the set screw 12 is an upwardly extending tubular support 14 50 which may be conveniently made of ordinary metal pipe and to the upper end of this support 14 is attached the oil tank 15 which may be of any suitable capacity. The bottom of this oil tank has extending downward 55 from it an annular flange or collar 16 concentric to the pipe 14 and extending

from the interior of the oil tank is a small tube or nipple 17 which is disposed close to this collar 16.

Loosely surrounding the lower end of the 60 pipe 14 and resting loosely upon the upper end of the base 10 immediately around the socket 11, is a conical or upwardly flaring casing 18 which, when the pipe 14 is disposed within its socket, extends nearly up 65 to the bottom of the container or tank 15. This casing at its upper end is formed with a plurality of perforations 19 or other apertures through which oil may pass onto the exterior of the casing, and the lower portion 70 of the casing is preferably roughened as by forming this lower portion with a large number of protuberances 20. The roughening of this casing may be also secured by attaching thereto wire netting, as 75 illustrated in my prior patent.

Within the upper portion of the casing there is formed a transversely extending annular floor or bottom 21 which at its center carries the upwardly extending sleeve 22, 80 whose upper edge may be notched or otherwise apertured for the passage of oil. This sleeve loosely surrounds the tubular support 14 and this sleeve is disposed between the tube 14 and the collar 16.

Disposed around the collar 16 and, therefore, between this collar and the casing, is a layer of felt or other fibrous absorbent material 23 which I will hereafter term a wicking, and disposed between the outer face 90 of the sleeve 22 and the inner face of the collar 16 is a wick 24 of like character. This wick is of such character that when squeezed it will exude oil.

The tank 15, as before stated, may be made 95 in any suitable manner and size and is provided with a top 25 having a filling opening normally closed by a cap 26 and having an aperture for the stem 27 of a valve 28. This valve may rest upon the seat 29 at the upper 100 end of the nipple 17 and in this case, of course, cuts off communication between the interior of the tank 15 and the oil chamber formed in the upper portion of the casing 18. When the device is in use, however, this 105 valve is raised by means of a nut 29 having screw-threaded engagement with the valve rod 27. When it is desired to fill this container, the nut 29 is turned up to permit the descent of the valve onto its seat. Then the 110 cap 26 is removed and the tank filled. When the tank is filled the valve 28 is again lifted

to permit oil to pass into the oil receiving space in the upper portion of the casing 18.

In the use of this device, it will be seen that when the hog rubs himself against the casing 18, the sleeve 22 will be forced laterally, thus compressing the wicks 23 and 24. This will cause the oil on the wick 23 to spurt out through the openings 19 onto the exterior of the conical casing and thus in the act 10 of rubbing, the hog will become covered with oil. At the same time the compression of the wick 24 causes oil to be exuded from the wick and pass over the upper edge of the sleeve 22 or through apertures in the 15 sleeve onto the inside face of the sleeve and thus trickle down this sleeve to the lower end of the supporting tube 14 and over the base 10 onto the platform 13, so that these parts are coated with oil and small pigs 20 who cannot operate the large oiler will collect oil from the platform.

I do not wish to be limited to the particular form of tank shown as any ordinary vacuum feed tank might be used of the same 25 character as is used on oil stoves. Obviously, also other details of construction might be changed without departing from the spirit of the invention as defined in the appended claims.

30 It is entirely possible to use an outer casing which is cylindrical instead of conical but which is rockingly mounted upon the base in the same manner as the casing 18. I wish it understood that, as specifically 35 defined, the casing may be of any desired form. I prefer the conical casing, however, for the reason that it overhangs the hog and as a consequence oil spurts out of the openings 19 upon the back of the hog whenever the casing is forced in with sufficient 40 pressure. The feed of oil through the openings 19 will depend upon the height of the oil within the chamber formed in the upper end of the casing and this in turn will depend upon the height to which the tank 15 is adjusted. Thus if it be desired to raise the level of the oil in the tank, the central support 14 is raised within the base and held in its adjusted position by the set screw 12 or if it be desired to lower the depth of the 45 oil, the support 14 is lowered. The nearer the oil is to the holes 19, the quicker the feed and the greater the amount of wicking disposed on each side of the plate 16, the less movement the casing 18 will have and, therefore, the less the oil will spurt out. If 50 the wicking is very loose, the casing 18 can have considerable movement before the wicking is compressed and, therefore, the oil 55 will spurt. If, on the other hand, there is considerable wicking on opposite sides of the collar 16 there will be less movement of the casing and a less spouting of the oil through the openings 19 and the oil will tend to ooze 60 out.

I claim:—

1. A hog oiler comprising a base having an upstanding support, a tank mounted upon the upper end of the support, a casing disposed concentric to the support and oscillatably mounted in connection therewith, the casing having an oil receiving space in its upper end and receiving oil from the tank, and means for causing the discharge of oil from said space onto the exterior of the casing when the casing is oscillated.

2. A hog oiler of the character described comprising a base, a support extending upward therefrom, an oil tank mounted upon the upper end of the support, a casing surrounding the support and oscillatable with reference thereto, the casing at its upper end being formed to provide an oil receiving space, a wick disposed on the inside face of the wall of the oil receiving space, and a member carried by the tank and extending down into said oil receiving space on the inside of the wick, and means for discharging oil from the tank into said space.

3. A hog oiler comprising a base, a support extending upward from the base, a tank mounted upon the upper end of the support, a casing concentrically disposed around the support and oscillatably mounted upon the base and support, said casing at its upper end being formed to provide an annular oil receiving chamber having an inner wall concentric to the support, an annular member mounted upon the tank and extending downward into said space between the inner 100 and outer walls thereof, and wicking disposed between said walls and said annular member.

4. A hog oiler comprising an oil tank, a casing disposed below the oil tank and mounted for oscillation in any direction in a plane extending through the axis of the casing, the upper end of the casing being formed to provide an annular oil receiving chamber having an inner wall and an outer 110 wall, a member extending downward from the bottom of the tank through the center of the casing, means connecting the tank to the chamber, a collar extending downward from the tank into the space between the outer 115 and inner walls of said chamber, and wicking disposed between said collar and the outer and inner walls, the wicking being adapted to be compressed by an oscillation of the casing to thereby cause oil to be exuded onto the outer face of the casing and the outer face of said concentrically disposed member.

5. In a hog oiler, a base, an upwardly extending support, an oil tank mounted upon the upper end of said support, an upwardly flaring conical casing surrounding the support below said tank and having rocking movement in all directions upon the support and the base, the upper end of said cas- 120 125 130

ing being formed to provide an annular oil chamber having an inner wall and an outer wall, both of said walls being apertured, an annular collar attached to the bottom of the 5 tank and extending downward into said chamber between said outer and inner walls, wicking disposed between said collar and the inner and outer walls, and means connecting the tank with said chamber.

10 6. In an oiler of the character described, a base, a casing movably mounted on the base and having an upper open end and having an oil receiving chamber at said upper end, a tank supported above the casing and having 15 a discharge pipe extending into the chamber, means whereby the tank may be raised or lowered relative to the casing to thereby control the height of oil within the casing and means causing the discharge of 20 oil from said oil receiving chamber upon the exterior of the casing as it is moved.

7. In an oiler of the character described, a casing having an open upper end and having an oil receiving chamber in its upper

end, a central supporting member extending 25 vertically through the casing, a base upon which the member is mounted for vertical adjustment independently of the casing, and a tank supported upon the supporting member above the casing and having a discharge 30 pipe extending into the chamber, the vertical adjustment of the central member acting to raise or lower the tank to thereby control the height of oil within said chamber.

8. A hog oiler comprising a base having 35 an upstanding support, a tank mounted upon the upper end of the support, the tank being vertically adjustable relative to the base, a casing disposed concentric to the support and oscillatably mounted in connection therewith and having an oil receiving space in its upper end, the tank having a nipple extending down into said space, and wicking disposed in said space.

In testimony whereof I hereunto affix my 45 signature.

ELMER R. CLEMENTS.
